WRENCH

Roy O. Wright, Huntington, W. Va., assignor of
one-half to James A. Miller, Huntington, W.
Va.

Application October 4, 1938, Serial No. 233,308

2 Claims. (Cl. 81—55)

My invention relates to improvements in wrenches and has as one of the principal objects thereof the provision of a wrench equipped with means operable for engagement with a pair of threaded elements whereby to secure one of said elements stationary while the other of said elements is actuated for adjustment, attachment or detachment relative to the first element.

Another object of my invention is to provide a wrench of the character described equipped with means for reliably securing one of a pair of nuts stationary while the other nut is adjusted relative thereto and which means is simple in construction, durable in use, efficient in operation and economical in manufacture.

Other objects and advantages will be apparent from the following description, appended claims and annexed drawing.

Referring to the drawing wherein like reference characters designate like parts throughout the several views:

Figure 1 is a side elevation of my invention.

Figure 2 is a sectional view taken on the line 2—2 of Figure 1.

Figure 3 is an end elevation of the detachable head member.

Figure 4 is a sectional view taken on the line 4—4 of Figure 2.

Figure 5 is a side elevation of the head member.

In practicing my invention I provide a wrench comprising a barrel 6 formed with a longitudinally extending bore 7, the ends of said bore being formed with oppositely disposed conical shaped countersinks 8 provided with lengthwise extending grooves 9. The outer ends of the barrel 6 are formed with enlarged sections 10 of hexagonal configuration in transverse section whereby the faces thereof are adapted for engagement with the jaws of a wrench or other similar tool for a purpose hereinafter more fully set forth.

A cylindrical shaped head member 11 is provided for association with one end of the barrel and comprises a body section 12 fashioned with a conical shaped shank 13 formed with lengthwise extending teeth 14 seating within the grooves 9 whereby to preclude rotation of said head relative to said barrel. The opposite end of the body 12 is fashioned with an enlarged section 15 formed therein with a hexagonal socket 16 which communicates with a cylindrical shaped socket 17 of a lesser diameter formed within the body section 12. The shank 13 is formed with a bore 18 communicating with the socket 17 and of

a lesser diameter than the latter to provide a shoulder or seat 19.

A pry or lever 20 of a substantially elongated cylindrical configuration is detachably and rotatably secured within the bore 7 and is fashioned at one end with a cylindrical shaped head 21 seated within the socket 17 and having an inwardly disposed face abutting the shoulder 19. Said head 21 is fashioned with a square shaped socket 22. The opposite end of the lever 20 extends an appreciable distance beyond the end of the barrel and is formed with an arcuate cuneiform shaped end 23 whereby the wrench 5 may be used as a pry. Inwardly of the end 23 the lever 20 is fashioned with a pair of oppositely disposed plane faces 24 adapted for engagement by the jaws of a wrench or other suitable tool.

In use, the parts being in the position illustrated in Figures 1 and 2 of the drawing, the socket is inserted over the sides of a hexagonal shaped nut, the latter forming one of a pair threaded on a shank or the like. The lever 20 is moved longitudinally a sufficient distance to permit insertion of the socket 22 over the sides of the other nut constituting the pair. Said barrel is held stationary by a wrench or similar tool engaging the faces of one of the sections 10 and the lever 20 is rotated by means of a wrench or the like engaging the faces 24 whereby the square shaped nut is moved relative to the hexagonal shaped nut.

It is to be understood that the lever 20 may be held stationary and the barrel 6 rotated to effect reverse adjustment between the nuts. In instances where it is desired to adjust nuts of different sizes, the head 11 may be substituted for a similar head adapted to the size of the nut and likewise the lever 20 may be substituted for a similar lever having a head equipped with a different size socket. It will be noted that the lever 20 through the medium of the head 21 thereof coacts to maintain the head 11 in connected relation with the barrel 6. Furthermore, the head 11 may be disengaged from one end of the barrel and inserted in the opposite end.

From the foregoing it will be apparent that I have provided a simple and efficient wrench so constructed and arranged as to permit relative adjustment of a pair of nuts without the use of additional means for securing one of said nuts stationary relative to the other during a desired adjustment.

It is to be distinctly understood that various changes and modifications may be resorted to in the construction and arrangement of the parts

without departing from the spirit of the invention or scope of the appended claims.

What I claim is:

- 5 1. A device of the character described, comprising, a barrel having a bore fashioned at one end with a toothed conical shaped countersink, a head fashioned with a nut receiving socket and with a toothed shank detachably carried within said countersink and effecting meshing of said teeth whereby said head is rotated by said barrel, and a readily detachable lever rotatably mounted in said bore and fashioned with a head formed with a nut receiving socket, said last mentioned head rotatably mounted in said first mentioned head and adapted to secure one of a pair of nuts for movement relative to the other when the latter is engaged by the socket of said first mentioned head and said barrel and lever subjected to relative rotation.
- 10 15 20 2. A device of the character described, com-

prising, a barrel having a bore fashioned at one end with a toothed conical shaped countersink, a head fashioned with a nut receiving socket and with a toothed shank detachably carried within said countersink and effecting meshing of said teeth whereby said head is rotated by said barrel, and a readily detachable lever rotatably mounted in said bore and fashioned with a head formed with a nut receiving socket, said last mentioned head rotatably mounted in said first mentioned head and adapted to secure one of a pair of nuts for movement relative to the other when the latter is engaged by the socket of said first mentioned head and said barrel and lever subjected to relative rotation, said barrel and said lever each provided with tool engaging faces adapted for engagement with tools whereby to effect relative movement of said barrel and lever.
